UNITED STATES PATENT OFFICE

MARGARET ELEANOR MCCOY, OF DULUTH, MINNESOTA

COMBINATION GARMENT

Application filed March 28, 1928. Serial No. 265,506.

The object of this invention is to provide a combination garment including four panels, that is, two side panels each of which forms a leg portion and a side member of a camisole; one back panel, the top of which forms the upper part of the camisole, and extending downwardly forms a shadow-proof sanitary apron; the fourth panel forming the front of the camisole, and extending downwardly and rearwardly, and widening out, and finally terminating at a point which is to be fastened to the central portion of the sanitary apron.

A further object is to produce, in the manner specified, and in one garment, the equivalent of a camisole, bloomer, and sanitary apron, the garment to be supported by a shoulder strap on each side.

A further object is to make unnecessary a dress slip, and to provide in the specially formed front panel, widened as indicated, ample freedom of movement, and to allow for adjustment of the effective length at the point of connection between this element and the sanitary apron.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a view of the garment in perspective, and showing the manner in which it is worn.

Figure 2 is a view in front elevation.

Figure 3 is a view in rear elevation, with portions in dotted lines.

Figure 4 is a view in vertical section, the section being on line 4—4 of Figure 2.

Figure 5 is a detail in section on line 5—5 of Figure 2 and showing fastening devices for one of the shoulder straps.

Figure 6 is a detail in section showing another of the fastening devices, the section being through the overlapping portions secured by elements 20, at the right of Fig. 2.

The side portions of the garment include

the upper side members 10 which may assume approximately the position of Figure 1, in use, one shoulder strap 11 being connected at 12 and 13, and the other strap 14 being secured at the back at the point 15 and being detachably connected at 16 with the side portion of the garment, near the front thereof, or near the arm of the wearer.

The rear panel of the garment, designated 17, has its edge portions connected with the edges of the sides 10, as shown at 18, and an opening is provided at 19, to be closed by co-operating fastening devices or the like, at 20. Rear panel 17 is connected with the sides 10 for a suitable distance, but the lower edge portions are free from the side portions where the bloomer legs 21 turn inwardly and are formed into cuff members.

A shadow-proof sanitary apron 24 of impervious material is secured to the inner side of the back panel, and the front member or panel of the garment has connection with apron 24, as described below.

An important feature of construction is the front panel 25, the edges of which are connected with the side panels 10, at the points 26, and this panel may first be slightly reduced in width at 27, and the material then widens, the lower part extends downwardly and rearwardly between the legs, and the end portion 28 is secured to the apron 24 at about the point designated 29—the connection being adjustable regarding length of the end portion or strap, and the fastening devices or portions at 29 being detachable. A plurality of buttonholes and one button, or a series of snap fasteners or the like, serve the purpose.

The garment at moderate cost serves as camisole, bloomer, sanitary apron, and dress slip.

Having described the invention what is claimed is:—

1. In a garment, a plurality of side portions and shoulder straps connected therewith, these portions constituting the sides of the body of the garment and having their lower ends formed into leg portions, a back portion connected with the edges of the upper part of the side portions, a thickness of impervious material connected with the inner

- side of the lower part of the back, a front portion connected with the front edges of the side portions of the garment and extending downwardly and then rearwardly and having adjustable connection with the inner side of the thickness of material secured to the back of the garment, said front portion having its lower end wider than the remaining portion of the front and having its edge portions secured between the leg portions.
- 10 2. In a garment, a plurality of members forming the sides of a waist portion and having their lower ends formed into legs, a back portion connected with said members, a thickness of impervious material connected with the inner side of the lower part of the back, a front portion connected with the front edges of said members first named, and extending downwardly and then rearwardly and having connection with the inner side of the thickness of material secured to the back of the garment, and means for suspending the waist portion.

In testimony whereof I affix my signature.

26 MARGARET ELEANOR McCOY.
